United States Patent Office

Des. 203,755
Patented Feb. 15, 1966

203,755

BALL CART OR THE LIKE

George E. Schaefer, Muskegon Heights, Mich., assignor to
Brunswick Corporation, Chicago, Ill., a corporation of
Delaware

Filed May 10, 1965, Ser. No. 85,201

Term of patent 14 years

(Cl. D34—5)

FIG. 1 is a front perspective view of the invention;
FIG. 2 is a rear perspective view of the ball cart illustrated in FIG. 1, taken from the same side as FIG. 1;

FIG. 3 is a side elevational view of the ball cart illustrated in FIGS. 1 and 2, taken from the side opposite that shown in FIGS. 1 and 2; and

FIG. 4 is a top plan view of the ball cart illustrated in FIGS. 1-3.

The dominant features of the design are shown in full lines on the drawing.

I claim:

The ornamental design for a ball cart or the like, as shown and described.
